(57) **CLAIM**

The ornamental design for a notebook computer with air tunnel cover, as shown and described.

DESCRIPTION

FIG. 1 is a perspective view of a notebook computer with air tunnel cover showing our new design;

FIG. 2 is a top view thereof;

FIG. 3 is an enlarged view of the indicated portion of FIG. 1;

FIG. 4 is a top view showing the air tunnel cover of the notebook computer separated from the computer and enlarged for clarity of illustration;

FIG. 5 is a perspective view of the notebook computer with air tunnel cover in an alternate position where the air tunnel cover is covered by the keyboard; and,

FIG. 6 is a perspective view thereof with the air tunnel cover covered by the keyboard and the display folded.

The front, rear, left side, right side and bottom views of the notebook computer with air tunnel cover are omitted because these views do not include any portions of the article that form part of the claimed design. The dashed broken lines illustrate portions of the notebook computer with air tunnel cover and form no part of the claimed design.
